(57) CLAIM

The ornamental design for an article holder having a suction cup for attachment to a bathroom wall, as shown and described.

DESCRIPTION

FIG. 1 is a top plan view of an article holder having a suction cup for attachment to a bathroom wall, showing the design; FIG. 2 is a right elevational view thereof, with the left elevational view being a mirror image of the right elevational view;

FIG. 3 is a bottom plan view thereof;

FIG. 4 is a front elevational thereof; and,

FIG. 5 is a rear elevational view thereof.
